PILE DRIVER ATTACHMENT FOR
PERCUSSIVE TOOLS

William A. Smith, Jr., North Arlington, N. J.,
assignor to Worthington Pump and Machinery
Corporation, New York, N. Y., a corporation of
Virginia

Application January 31, 1934, Serial No. 709,125

6 Claims. (Cl. 61—76)

This invention relates to pile drivers and more particularly to a pile driving attachment for percussive tools of the hammer type.

An object of the present invention is to provide a pile driving attachment as specified which is rugged in construction, durable and embodies adjustable plates or guides for guiding a pile during the driving operation.

With these and other objects in view as may appear from the accompanying specification, the invention consists of various features of construction and combination of parts, which will be first described in connection with the accompanying drawings, showing a pile driving attachment for percussive tools of the preferred form embodying the invention, and the features forming the invention will be specifically pointed out in the claims.

In the drawings:

Fig. 1 is a longitudinal section through the improved pile driving attachment showing it applied to a fragment of an approved type of percussive tool.

Fig. 2 is a side elevation of a fragment of the pile driving attachment and taken on the line 2—2 of Fig. 1.

Fig. 3 is a longitudinal section through a modified form of the pile driving attachment.

Fig. 4 is a section on the line 4—4 of Fig. 3. Referring more particularly to the drawings, a percussive tool of any approved type embodying a cylinder 1 in which the piston 2 reciprocates, is shown in fragment in Fig. 1 of the drawings. The cylinder 1 has a front head 3 attached thereto by means of bolts 4 in the usual manner and a front head bushing 5 is provided which serves as a guide for the stem 6 of the anvil block or pile striking member 7.

The front head 3 has extensions 8 and 9 formed thereon which project outwardly from the front head and are spaced one from the other to receive a pile indicated at (A) in dot and dash lines, and between.

In operation, the piston 2 is reciprocated by fluid, under pressure in the usual manner of percussive tools and this hammer piston tool striking the anvil block or pile striking member 7 imparts blows to the pile (A) for driving it.

Piles of different widths or thicknesses are frequently driven, and to provide for the proper guiding and steadyng of such piles during the driving operation, cheek plates 9a and 10 are provided which slide in suitable guide recesses 11 formed in the extensions 8 and 9. The cheek plates 9a and 10 are adjusted to vary the

distance between their facing sides, to accommodate different widths or thicknesses of piles (A) by means of adjusting screws 12. The adjusting screws 12 are threaded into the cheek plates 9a and 10 and are rotatably mounted in the extensions 8 and 9. Collars 13 are formed on the adjusting screws 12 and are engaged by clamping nuts 14 for preventing longitudinal movement of the adjusting screws 12. The clamp nuts 14 are of sufficient size to permit the withdrawal of the adjusting screws 12 from the front head extensions 8 and 9.

Stop shoulders 15 are formed on the inner sides of the front head extensions 8 and 9 and limit the forward or outward movement of the anvil block or pile striking member 7.

A step or foot rest on which the operator may rest his foot 16 is detachably attached to the front head extension 8.

In Fig. 1 of the drawings, the cheek plates 9a and 10 are guided in their movement by the walls of the cheek plate receiving recesses formed in the front head extensions 8 and 9, while in the modified form shown in Figs. 3 and 4 the adjustable cheek plates are guided by means of stems formed thereon which engage in suitable bores in the front head extensions.

Referring specifically to the modified form, the front head extensions 8' and 9' have stops 15 formed thereon which limit the movement 30 of the anvil block 7' in the same manner in which the stops 15 limit the movement of the anvil block 7. The extensions 8' and 9' are attached to the cylinder (not shown) in any suitable manner and they have laterally extending 35 bores 20 formed therein which receive the stems 21 of the adjustable cheek plates 22 and 23. The cheek plates 22 and 23 are adjusted to regulate the distance between their facing surfaces by means of adjusting screws 12' which thread 40 into the adjustable cheek plates and rotate in the extensions 8' and 9'. The adjusting screws 12' are held against longitudinal movement in the front head extensions 8' and 9' by flanges or collars 13' and clamping nuts 14', while the 45 adjustable cheek plates 22 and 23 are held against rotation relative to the front head extensions by means of any suitable type of keys 24 which engage in suitable keyways 25.

A step 16' is attached to the front head extension 8'.

While in the drawings the adjustable cheek plates 9a and 10 and 22 and 23 are shown as circular, it is to be understood that they may be any desired shape without departing from the 55

spirit of the present invention, and also the rotary movement, cheek plates connected to said drawings showing the lowermost or outermost edges of the adjustable cheek plates being positioned inwardly of the outermost ends of the front head extensions but this is a detail which may be departed from in actual construction if found desirable. 5

It will be understood that the invention is not to be limited to the specific construction or arrangement of parts shown, but that they may be widely modified within the invention as defined, by the claims. 10

What is claimed is:

1. In a pile driving attachment for percussive tools, a pile striking member, a front head, extensions on said front head for guiding said striking member, cheek plates carried at the inner facing sides of said extensions, adjusting screws rotatably carried by said extensions and 15 adjustably connected to said cheek plates for adjusting the relative positions of the facing surfaces of the cheek plates, and means on said extensions for limiting the outward movement of said striking member. 20
2. In a pile driving attachment for percussive tools, a pile striking member, a front head, extensions on said front head, adjusting screws carried by said extensions and held against all movement with respect to said extensions except 25 rotary movement, and cheek plates connected to said adjusting screws for movement towards or from each other on rotary movement of the screws. 30
3. In a pile driving attachment for percussive tools, a pile striking member, a front head, extensions on said front head, adjusting screws carried by said extensions and held against all movement with respect to said extensions except 35

adjusting screws for movement towards or from each other on rotary movement of the screws, and stops formed on said extensions for limiting the movement of said striking member, said stops serving as guides for said cheek plates. 5

4. In a pile driving attachment for percussive tools, a pile striking member, a front head, extensions on said front head, adjusting screws carried by said extensions and held against all movement with respect to said extensions except 10 rotary movement, cheek plates connected to said adjusting screws for movement towards or from each other on rotary movement of the screws, means for preventing rotary movement of said 15 cheek plates, and means for preventing longitudinal movement of said adjusting screws. 20

5. In a pile driving attachment for percussive tools, a pile striking member, a front head, extensions on said front head, said extensions provided with recesses in their facing sides, adjusting screws carried by said extensions and projecting into said recesses, and cheek plates mounted on said adjusting screws for movement into and out of said recesses upon rotation of 25 the screws. 30

6. In a pile driving attachment for percussive tools, a pile striking member, a front head, extensions on said front head, said extensions provided with recesses in their facing sides, adjusting screws carried by said extensions and projecting into said recesses, cheek plates mounted on said adjusting screws for movement into and out of said recesses upon rotation of the screws, means for preventing rotary movement of said 35 cheek plates, and means for preventing longitudinal movement of said adjusting screws. 40
